UNITED STATES PATENT OFFICE.

GEORGE T. WILSON, OF BOSTON, ASSIGNOR OF ONE-HALF TO JULIAN D'ESTÉ, OF SALEM, MASSACHUSETTS.

VALVE.

SPECIFICATION forming part of Letters Patent No. 359,949, dated March 22, 1887.

Application filed January 8, 1887. Serial No. 213,768. (No model.)

To all whom it may concern:

Be it known that I, GEORGE T. WILSON, of Boston, in the county of Suffolk and State of Massachusetts, have invented a new and useful Improvement in Valves, of which the following is a specification.

The object of the invention is to provide a valve apparatus to regulate the passage of vaporous and gaseous substances, especially steam, so arranged that, first, such a substance may pass through the valve-seat to the outlet-pipe until the back-pressure it exerts has reached the maximum pressure it is intended it should exert and tends to rise above it, and that then it should cease to pass through; and, that, second, such a substance may not pass through the valve-seat to the outlet until it exerts the maximum pressure it is intended that it should exert, and that it should cease to pass through when the pressure it exerts is less than the maximum back-pressure intended.

In my invention the valve-seat has a prolongation provided with a port or ports, preferably the latter, around which the main valve fits tightly. The prolongation of the valve-seat is further provided with a valve-seat valve.

To attain the object of my invention above numbered "first," said valve-seat valve is kept open by a force equal to the maximum pressure it is intended that the back-pressure should exert, in order that steam may pass through the prolongation of the valve-seat to the inner area of the main valve and raise said main valve and open said ports to the passage of steam, the valve-seat valve closing when it is relieved of said force, allowing thereby the valve-closing spring to close said main valve and shut said ports to the passage of steam.

To attain the object of my invention above numbered "second," said valve-seat valve is kept closed by a force equal to the maximum pressure—high pressure—it is intended should be exerted, said valve-seat valve opening when relieved of said force, in order that steam may pass through the prolongation of the valve-seat to the inner area of the main valve, and raise said main valve against the pressure of the valve-closing spring and open said ports to the passage of steam.

In the drawings, Figure 1 represents a sectional elevation of an apparatus embodying my invention, arranged to attain the object of my invention above numbered "first." Fig. 2 55 represents a sectional elevation of a modification of the apparatus shown in Fig. 1, arranged to serve as a relief-valve to attain the object of my invention above numbered "second."

In Fig. 1, C is the valve case, which has the inlet A' and outlet B'. The valve seat T' has the prolongation G', which is provided with the ports P', and is also provided with the valve-seat valve v, as shown. The valve-stem r of this valve v passes through the opening M in the prolongation of the valve-seat, and passes loosely through the valve V' to admit of a slight leakage of steam to avoid forming temporarily a cushion when the valve V' closes, 70 and is provided with a nut, n, and carries a spring, s, as shown. The prolongation G' has the packing-grooves w w. s' is the valve-closing spring, compressed between the valve-case cap K' and the shoulder h of the valve V' when 75 the valve V' is raised. The valve-case cap K' has the perforations f for the passage of steam to the diaphragm D. The cover U' screws to the valve-case C and contains the spring S', through which passes the rod R'. This rod R' 80 is provided with the disk Q, against which the spring S' bears when the compressing-nut N', which turns in the cover U', is turned against the spring S', compressing said spring, and causing the disk Q to bear through the dia- 85 phragm D upon the nut n of the valve-stem r, and thereby open the valve-seat valve v.

The operation is as follows: The compressing-nut N' is turned against the spring S', and the spring compressed thereby sufficiently to 90 resist a pressure not greater than the maximum pressure intended. The spring S', by means of the disk Q, bears through the dia- 95 phragm D upon the valve-stem r, and forces said valve-stem down against the lifting force of the spring s, opening thereby the valve-seat valve v. Steam enters through the inlet A' into the prolongation G' of the valve-seat, passes through the opening M, and presses against the inner area, L', of the valve V', 100 and lifts this valve V' against the pressure of the valve-closing spring s', opening thereby

the ports P' of the valve-seat, through which steam passes to the outlet B' . The steam also fills the valve-case C' and passes through the perforations f in the valve-case cap K' , and 5 presses against the diaphragm D . The steam, pressing against the diaphragm D , when it exerts the maximum pressure intended and tends to rise above it, forces up the disk Q and spring S' , and thereby relieves the valve-stem 10 r of the pressure upon it. The spring s then raises the valve-stem r , closing thereby the valve-seat valve v , and the spring s' closes the main valve V' around the ports P' —steam in the valve V' leaking out, as above explained— 15 and shuts off the passage of steam through the valve-seat, the main valve V' remaining closed so long as the pressure of steam—back-pressure—upon the diaphragm D is as great as the maximum back-pressure intended. 20 In Fig. 2 it will be seen, by comparison of that figure with Fig. 1, that the principal differences in arrangement of the apparatus shown in those figures are that the valve V^2 of Fig. 2 is the valve V' of Fig. 1 inverted; that 25 the valve-seat T^2 and its prolongation G^2 of Fig. 2 are the valve-seat T' and its prolongation G' of Fig. 1 inverted, and that the valve-seat valve v^2 is seated over the opening M^2 in the valve-seat prolongation of the apparatus shown 30 in Fig. 2, instead of, as in Fig. 1, passing through the opening M of that figure. The operation is as follows: The compressing-nut N^2 is turned against the spring S^2 , and the spring compressed sufficiently thereby to 35 resist a pressure not greater than the maximum pressure intended. The spring S^2 , by means of the disk Q^2 , bears through the diaphragm D^2 upon the valve-stem r^2 , and forces said valve-stem down against the lifting force of 40 the spring s^2 , seating the valve-seat valve v^2 over the opening M^2 of the prolongation G^2 of the valve-seat, and keeping said opening closed.

Steam enters through the inlet A^2 , and passing through the perforations f^2 in the valve-case cap K^2 presses against the diaphragm D^2 . 45 The steam, pressing against the diaphragm D^2 , when it exerts the maximum pressure intended and tends to rise above it, forces up the disk Q^2 and the spring S^2 , and thereby relieves the valve-stem r^2 of the pressure upon it. The spring s^2 then raises the valve-stem r^2 and lifts the valve-seat valve v^2 from its seat over the opening M^2 . Steam then passes through this opening M^2 and presses against the inner area, L^2 , of the main valve V^2 , and lifts this valve V^2 55 against the pressure of the valve-closing spring s^3 , opening thereby the ports P^2 of the valve-seat prolongation, through which steam escapes to the outlet B^2 until the pressure of steam upon the diaphragm D^2 is less than the maximum pressure intended, when the spring S^2 , by means of the disk Q^2 , bears through the diaphragm D^2 upon the valve-stem r^2 , and forces said valve-stem down and seats the valve-seat valve v^2 over the opening M^2 , closing said opening and shutting off the passage of steam to the inner area, L^2 , of the main valve V^2 . The valve-closing spring s^3 then closes the valve V^2 around the ports P^2 , shutting off the escape of steam to the outlet B^2 ; the small 60 opening x in the main valve V^2 admitting of a slight leakage of steam to avoid forming temporarily a cushion when the valve V^2 closes. 70

I claim—

In a valve apparatus, the combination of a 75 main valve, main valve-closing spring, valve-seat having a prolongation provided with a port or ports, and a valve-seat valve operated substantially as set forth, substantially as described, for the purpose specified.

GEORGE T. WILSON.
